Primary Examiner — Catherine S Posthauer*Assistant Examiner* — Joan E. Diehl(74) Attorney, Agent, or Firm — Fross, Zelnick, Lehrman & Zissu, PC; Charles T. J. Weigell, Esq.(57) CLAIM

The ornamental design for a combined bottle and cap for cosmetics as shown and described.

DESCRIPTION

FIG. 1 is a top perspective view of a combined bottle and cap for cosmetics showing my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the figures depict portions of the combined bottle and cap for cosmetics that form no part of the claimed design.
